UNITED STATES PATENT OFFICE.

JOHN F. STANDISH, OF WINTHROP, MASSACHUSETTS, ASSIGNOR TO UNITED SHOE MACHINERY COMPANY, OF PATERSON, NEW JERSEY, A CORPORATION OF NEW JERSEY.

WORK-SUPPORT.

1,237,402.

Specification of Letters Patent. Patented Aug. 21, 1917.

Application filed November 16, 1914. Serial No. 872,460.

To all whom it may concern:

Be it known that I, JOHN F. STANDISH, a citizen of the United States, residing at Winthrop, in the county of Suffolk and 5 State of Massachusetts, have invented certain Improvements in Work-Supports, of which the following description, in connection with the accompanying drawings, is a specification, like reference characters on 10 the drawings indicating like parts in the several figures.

The invention to be hereinafter described relates to work supports, and more particularly to supports of the type for holding 15 lasts while operations are performed upon the shoes assembled thereon.

In attaching heels to shoes while on the wooden lasts, it is the common practice to support the last with the shoe thereon in a 20 position opposed to the heel to be attached and during the attaching operation to subject the heel to considerable pressure which is transmitted through the last to a last support or abutment opposed to the top or 25 crown of the last. It is frequently found that after lasts have been used for a time they have become broken down at one side of the top or crown, so that they no longer 30 present a proper and uniform bearing upon the support to which the crown of the last is opposed in the heeling machine, with the 35 result, that when pressure is applied during the heel attaching operation, there is a marked tendency for the shoe to tilt sideways, the heel seat of the shoe sliding transversely upon the heel. This tendency becomes 40 particularly emphasized when the heel seat is covered with wet glue and consequently quite slippery.

It is the purpose of the present invention to provide a work support which shall be self-adaptable to the conditions presented by the top or crown of the last, to the end 45 that pressure applied therethrough shall be transmitted in such uniform manner over substantially the entire top or crown surface of the last that all tendency for the shoe to tilt under the heeling pressure may be effectively overcome. To this end, an important 50 feature of the present invention consists in a last-contacting or pressure-transmitting element which is mounted upon a jack or support in such manner as to be self-adaptable to the top or crown surface of the last

by movement about an axis passing longitudinally through the crown surface of the last. Another important feature of the invention consists in such pressure-transmitting element adapted to rock about an axis passing longitudinally through the crown 55 of the last, and members to engage the sides of the last as the last and pressure transmitting element are brought into pressure relation. These and other features of the present invention will best be made clear from 60 the following description and accompanying drawings which set forth good practical forms thereof, and wherein the invention is shown as applied to a jack post, it being understood, however, that it may be otherwise 65 employed within the true scope of the invention as defined by the claims.

In the drawings:

Figure 1 is a perspective view of a work support embodying one form of the present 75 invention;

Fig. 2 is a central vertical longitudinal section of the parts at the end portion of the work support shown by Fig. 1;

Fig. 3 is a section of the parts on the line 80 3—3, Fig. 2, showing a last associated therewith;

Fig. 4 is a detached view of the last bed 85 piece supporting member showing the parts thereof separated;

Fig. 5 is a perspective view similar to Fig. 1, showing a modified form of work support embodying a form of the invention;

Fig. 6 is a central vertical and longitudinal section of the parts shown by Fig. 5; 90 and

Fig. 7 shows parts of the work support detached and in separated relation to more clearly illustrate their manner of assemblage.

Referring to Fig. 1: the jack post 1 may 95 be of any appropriate character suitable for use in connection with machines for manufacturing shoes, but in the present exploitation of the invention, is shown as of the character now common in a type of heeling machine, wherein the jack post is provided with means for detachable connection with a swinging jack post support. The jack post has a collar 2, a spindle 3, and catch 4 whereby it may be readily connected to or 100 detached from the jack post support, but as these features form no essential part of the present invention and are well understood 105

by those familiar with such machines, further detail description is unnecessary.

Mounted in the lower portion of the jack post 1 is a block 5 having an upwardly-extending portion 6 loosely mounted on a pin 7 and provided with teeth, by which it may be locked in desired relation with the jack post, as usual in this type of work supports. Certain features of the present invention, as will hereinafter more fully appear, are well adapted for association with a block, such as 5, capable of being swung or tilted in a plane extending longitudinally of the shoe in order to properly position the parts in a longitudinal plane in conformity with the requirements of the work, but such construction is not always essential.

The present invention contemplates primarily that the work support shall have an element which shall be self-conformable to the top or crown surface of a last, and that such conformation shall be effective prior to the application of the full pressure transmitted through the last during the heel-attaching operation. This feature of the invention is of particular importance in the use of lasts, the tops or crown portions of which have been broken down at one side. It also has in contemplation, a substantially free lateral or transverse movement of such element to bring the same in proper coacting relation with the top or crown of the last. As a means to this end, the jack post is provided with a last bed piece supporting member movable transversely with respect thereto, and carrying a last bed piece which is connected to the last bed piece supporting member for tilting movement about an axis passing through the top or crown portion of the last.

In the illustrated form of the invention, the block 5 is provided with a transversely-extending recess 8, preferably undercut as shown by Figs. 1 and 2 at 9, in which slides transversely a block 10 preferably having shouldered portions 11 for engagement with the undercut portions 9 of the recess 8, the construction being such that the block 10 as will hereinafter more fully appear, may have sliding movement transversely of the jack post. The transversely-extending recess 8 is of somewhat greater depth vertically than the shouldered portions 11 of the block 10, the construction being such that the block 10 may have bodily movement toward and from the bottom of the transversely-extending recess 8 as will be readily apparent.

Secured to the block 10 by suitable means such as the screw 13, is a last bed piece supporting member 12 having a transverse recess 14 to engage the downwardly-extending flanged portions 15 of the block 10, the construction being such that the block 10 and the last bed piece supporting member are rigidly united. The upper surface portion

of the last bed piece supporting member 12 on either side of the recess 14 is provided with a series of corrugations or teeth 16, which are adapted to interlock at times with a series of corresponding teeth or corrugations 17 on the surface of the block 5, substantially as indicated in Fig. 1.

In order that the last bed piece supporting member and its connected block 10 may have free transverse bodily movement with respect to the jack post 1, means are employed for normally maintaining the teeth or corrugations 16 and 17 disengaged. As a means to this end, the block 10 is provided with pins 18, Fig. 4, normally under the influence of springs 19 tending to project the pins upwardly from the top surface of the block 10 and against the upper wall of the transversely-extending recess 8, the construction being such that in the absence of force tending to move the jack post or block 5 and the last bed piece supporting member in a direction of relative approach, the spring-actuated pins 18 serve to hold said block 10 and its connected last bed piece supporting member in position with the teeth or corrugations 16 and 17 disengaged.

From the construction thus far described, it will be apparent that the last bed piece supporting member 12 is movable with substantial freedom in a direction transverse to the jack post under normal conditions when the teeth or corrugations 16 and 17 are disengaged; and in order to prevent complete removal of the last bed piece supporting member from the jack post, a stop is provided to limit such transverse movement.

In the present form of the invention, the stop comprises a pin 20 carried in a suitable recess in the jack post block 5, and having its end portion adapted to engage a recess 21 extending into the last bed piece supporting member, substantially as indicated in Figs. 2 and 4. The stop 20 or like device, is provided with means for manual manipulation, which in the present form of the invention, is shown as a hand screw 22 extending through a slot 23 in the block 5, the construction being such that upon raising the stop 20 from its engagement with the slot 21 in the last bed piece supporting member, the latter may be entirely removed from the jack post.

The last bed piece supporting member 12 is provided with downwardly projecting wing portions 24, 24, which are adapted to embrace the side portions of the last 25 at opposite sides of the top or crown thereof, as indicated in Fig. 3. Between the wing portions 24 and 24, the last bed piece supporting member is provided with a recess 26 for the reception of the last bed piece 27 and connections are provided between the last bed piece supporting member and the last bed piece to permit the latter to tilt 130.

about an axis passing through the top of the last.

As a preferred means to this end, the last bed piece 27 and the recess 26 in the last bed piece supporting member for the reception of said last bed piece, are preferably made with cylindrical contacting surfaces formed about an axis passing through the central lower surface of the last bed piece and consequently through the top or crown portion of the last in contact therewith. Any suitable means may be employed to connect the last bed piece supporting member and the last bed piece with permissive tilting movement of the latter about a longitudinal axis passing centrally through the face of said last bed piece, and as one form of means to this end, the last bed piece supporting member 12 is provided at its end portions with the recesses 28, Fig. 4, in which are secured the lugged brackets 29, as by means of the screws 30, said lugged brackets 29 each having inturned lugged portions 31 to engage slots 32 formed in the end portions of the last bed piece and in the arc of a circle concentric with the cylindrical surface of the last bed piece,—the construction being such that the lugged brackets 29 permit free tilting movement of the last bed piece about its longitudinal axis passing through the top or crown portion of the last engaged by it.

From the construction described, it will be apparent that prior to the application of pressure through the last during the heeling operation, the crown or top portion of the last may be properly seated against the face of the last bed piece, and that the latter will automatically conform its contacting surface with the top or crown of the last, and that prior to such application of pressure, the last bed piece supporting member carrying the last bed piece, may be moved transversely of the jack post into an appropriate position as demanded by the work under treatment. Upon the application of pressure after the parts have been thus positioned, the teeth or corrugations 16 and 17 are brought into interlocking engagement and further transverse movement of the last bed piece supporting member is precluded, so that during the heeling operation, the parts of the work support remain in a position assumed by them under the demands of the work.

Referring to Figs. 5, 6 and 7, as illustrative of a modified form of the invention: the jack post 1 is provided with a transverse slot or recess 33 substantially cylindrical in form, which is engaged by a cylindrical projection 34 extending from the last bed piece supporting member 35, the opposed end portions 36, 37 of the jack post and last bed piece supporting member being inclined or cutaway, the construction being

such that the last bed piece supporting member 35 may tilt in a plane extending longitudinally of the shoe to conform to the different longitudinal contours presented by the top or crown of different lasts.

The cylindrical portion 34 of the last bed piece supporting member 35 has a groove 38 into which projects the end of a spring 39 secured to the jack post 1, substantially as indicated in Fig. 6, the construction being such that while the last bed piece supporting member may tilt in the longitudinal plane of the work as hereinbefore stated, the spring 39 will normally act to maintain the last bed piece supporting member in position as indicated in Fig. 6.

The last bed piece supporting member 35 is movable bodily in a transverse direction of the jack post and to prevent entire withdrawal of the last bed piece supporting member from its connection with the jack post, there is provided a stop in the form of a pin 40 normally under the influence of a spring 41, said pin 40 being adapted to engage a recess 42 in the side of the cylindrical portion 34, the construction being such that while the last bed piece supporting member may be moved freely in a transverse direction with reference to the jack post, it is limited in such movement by the pin and slot 42. In order to permit the last bed piece supporting member to be withdrawn from the jack post, the pin 40 is provided with a hand-piece 43 which projects through a slot 44 of the jack post, whereby the stop pin 40 may be raised against the action of the spring 41 and disengaged from the recess 42 of the last bed piece supporting member.

The last bed piece supporting member 35 is provided with the side wings 45 and a curved seat 46 for the reception of the last bed piece 47, the wall of said recess 46 and the opposed surface of the last bed piece 47 being formed cylindrical and about an axis passing longitudinally and centrally through the face 48 of the last bed piece 47.

In the form of the last bed piece shown by Fig. 7, a lug 49 is provided which engages a suitable recess in the curved recessed face of the last bed piece supporting member substantially as indicated in Fig. 6, and serves as a limiting stop to the tilting movement of the last bed piece, although such stop is not always essential.

The last bed piece 47, like the last bed piece 27, has a plane or flat face to contact with the top or crown of the last and may be secured to the last bed piece supporting member by suitable means permitting tilting movement of the last bed piece about its axis passing centrally and longitudinally through the face thereof. As an appropriate means to this end, the last bed piece supporting member may be provided with the

lugged brackets 50 similar to the lugged brackets 29 heretofore described, and these may be secured in suitable recesses 51 at the ends of the last bed piece supporting member by suitable means such as the screws 52. Inwardly projecting lugs carried by these brackets extend into the curved recesses 54 at the end portions of the last bed piece, the construction being such that while the lugged brackets 50 maintain the last bed piece in coöperative relation with the last bed piece supporting member, they, in connection with the slots 54, permit the last bed piece to tilt about its axis extending longitudinally and centrally of the face thereof, and perforce, the top or crown portion of a last engaged by it.

From the construction described, both in the preferred and modified forms of the invention, it will be apparent that the last bed piece by its capacity for tilting movement about a center passing through the top or crown portion of the last, is enabled to assume a proper bearing relation with the top or crown portion of the last, even though the latter may be broken down, and that the pressure incident to the heeling operation will be transmitted through the last without danger of causing the heel seat to slip or tilt sidewise, as would be the case under unequally-distributed pressure.

What is claimed is:—

1. In a work support, the combination of a jack post, a last bed piece supporting member movable in a plane transversely of the work, members for engaging the sides of the last, a last bed piece to engage the top or crown of a last between said side members, and connections between the last bed piece and last bed piece supporting member constructed and arranged to permit rocking movement of the last bed piece about a center passing through the top or crown of the last.

2. In a work support, the combination of a jack post, a laterally movable last engaging member having a pinless engaging surface to engage the top of a broken-down last, and means connecting the jack post and last-engaging member to permit rocking movement of the last-engaging member about an axis passing longitudinally through the top of the last and enable the pinless last-engaging member to automatically conform in inclination to the top of the last upon application of pressure between the last and last-engaging member.

3. In a work support, the combination of a jack post, a last bed piece supporting member connected to the jack post for movement in a plane transversely of the jack post, and having side members for engaging the sides of the last, a last bed piece having a pinless engaging surface to engage the top or crown of a last, and connections between

the last bed piece and last bed piece supporting member constructed and arranged to permit free rocking movement of the last bed piece about an axis passing longitudinally of the last through the surface at the top or crown of the last.

4. In a device of the character described, a last engaging member for engaging the top or crown portion of a last, a support for said last engaging member having projecting members for engaging the sides of the last, and connections between the support and said last engaging member constructed and arranged to permit free rocking movement of the last engaging member relative to said support about an axis passing longitudinally through the top of the last engaged by said last engaging member.

5. In a device of the character described, the combination of a jack post, a last bed piece supporting member connected to the jack post for movement transversely thereof and provided with a recess having side portions to embrace the sides of a last, and a last-engaging member seated in said recess for rocking movement about a center passing longitudinally through the top of the last to cause the last-engaging member to automatically conform to the top of the last as the last and last-engaging member are pressed together.

6. In a work support, the combination of a jack post, a last bed piece having a pinless engaging surface constituting the sole engaging means between said last bed piece and the last, a last bed piece supporting member, said last bed piece and last bed piece supporting member having cylindrically formed engaging surfaces, and means connecting the last bed piece and last bed piece supporting member constructed and arranged to permit the last bed piece to automatically rock about an axis passing longitudinally through the top or crown of a broken down last when the last and last-engaging member are pressed together.

7. In a work support, the combination of a jack post, a last bed piece having a pinless engaging surface for engaging the top or crown of a last, a last bed piece supporting member movable transversely of the jack post, members for engaging the sides of the last and movable with the last bed piece supporting member, said last bed piece and last bed piece supporting member having cylindrically formed engaging surfaces, and means connecting the last bed piece and last bed piece supporting member at the ends thereof constructed and arranged to permit the last bed piece to rock about an axis passing longitudinally through the top or crown of the last.

8. In a device of the character described, the combination of a last engaging member for engaging the top or crown of a last, a

- jack post for said last engaging member and connections between the last engaging member and said jack post constructed and arranged to permit movement of the last-engaging member to different operative positions in each of three directions to conform the last-engaging member to the top of the last, one in a vertical plane extending longitudinally of the last, another in a horizontal plane extending transversely of the last, and a third in a vertical plane extending transversely of the last and about an axis extending longitudinally through the top or crown of the last.
- 15 9. In a device of the character described, the combination of a last engaging member for engaging the top or crown of a last, a support for said last engaging member provided with wing portions to embrace the sides of a last, said support and last engaging member having cylindrically curved bearing surfaces the axis of which extends longitudinally in the plane of the top or crown of the last, and connections between the support and last engaging member constructed and arranged to permit free rocking movement of the last engaging member about the said axis.
- 10 10. In a shoe support, the combination of a jack post, a last bed piece supporting member connected to the jack post and having side wing portions for embracing the sides of the last, and a last bed piece disposed between the side wing portions for engaging the top or crown of the last constructed and arranged for free rocking movement about an axis passing longitudinally through the plane of the top or crown of the last.
- 15 11. In a shoe support, a jack post, a last bed piece supporting member connected to the jack post for tilting movement in a vertical plane longitudinally of the last, a pinless last bed piece, and connections between the last bed piece and said supporting member constructed and arranged to permit automatic rocking movement of the last bed piece about an axis extending longitudinally in the plane of the top of the last to conform to the inclination thereof when the last and last bed piece are pressed together.
- 20 12. In a shoe support, a jack post, a last bed piece supporting member connected to the jack post for tilting movement in a vertical plane longitudinally of the last, a spring normally acting to return the supporting member in either direction to initial position, a last bed piece, and connections between the last bed piece and said supporting member constructed and arranged to permit rocking movement of the last bed piece about an axis extending longitudinally in the plane of the top of the last.
- 25 13. In a shoe support, a jack post having a transverse cylindrically shaped recess, a last bed piece supporting member having a portion to engage said recess and permit the said member to tilt in a vertical plane longitudinally of the last, a spring acting on said portion to normally maintain the said member in initial position, a last engaging member to engage the top or crown of a last, and connections between the said members constructed and arranged to permit rocking movement of the last engaging member about an axis extending longitudinally in a plane passing through the top or crown of the last.
- 30 14. In a shoe support, a jack post, a last bed piece supporting member, a last engaging member having a pinless engaging surface to engage the top of the last, and connections between the last bed piece supporting member and last engaging member permitting the last engaging member to rock about an axis passing longitudinally through the top of a last and enable the last engaging member to freely conform in inclination to the top of a broken down last unrestricted by the angular relation of said top and the last pin socket.
- 35 In testimony whereof I have signed my name to this specification in the presence of two subscribing witnesses.
- JOHN F. STANDISH.
